UNITED STATES PATENT OFFICE.

GABY H. WATERS, OF CLARENCE, SOUTH CAROLINA.

DESIGN FOR A CLOTHES-PIN.

SPECIFICATION forming part of Design No. 31,438, dated August 22, 1899.

Application filed July 15, 1899. Serial No. 724,003. Term of patent 7 years.

To all whom it may concern:

Be it known that I, GABY H. WATERS, a citizen of the United States, residing at Clarence, in the county of Spartanburg and State of South Carolina, have invented and produced a certain new and original Design for Clothes-Pins; and I do declare the following to be a full, clear, and exact description of the invention, such as will enable others skilled in the art to which it appertains to make and use the same.

The invention has relation to a new and original design for a clothes-pin; and it consists of a design of the configuration shown in the accompanying drawings, in which—

Figure 1 is a front elevation of the clothes-pin. Fig. 2 is a side elevation. Fig. 3 is a top plan view.

The leading feature of the design consists of the side pieces 1, the upper ends of which are bent outward, as shown at 2, thence ex-

tend downward, as shown at 3, and are curved laterally, as shown at 4, thence upwardly, as shown at 5, and thence terminate in the bowed cross-piece 6, while the lower ends bulge outwardly, as shown at 7, and thence meet, as shown at 8, where one of the parts projects outwardly, as shown at 9, and thence upwardly, as shown at 10, thence curved rearwardly, as shown at 11, and thence downwardly on the opposite side of the bowed portion 6.

What I claim is—

The design for a clothes-pin, as herein shown and described.

In testimony whereof I have hereunto set my hand in presence of two subscribing witnesses.

G. H. WATERS.
